UNITED STATES PATENT OFFICE

JOHN C. STATON, OF ATLANTA, GEORGIA, ASSIGNOR TO THE COCA-COLA COMPANY, OF ATLANTA, GEORGIA, A CORPORATION OF DELAWARE

REFRIGERATOR

Application filed January 9, 1929. Serial No. 331,168.

The invention relates to bottle refrigerators and has as an object the provision of a device for cooling bottles or other containers as of soft drinks, and enabling ready access 5 to the same for dispensing purposes.

It is a further object of the invention to provide a device of the class referred to that may be knocked down for transportation.

It is a further object of the invention to 10 provide such a device having means for holding container racks to make the bottles or the like carried thereby readily accessible for replacements.

It is a further object of the invention to 15 provide a device of this class wherein the heat insulation is protected from the effect of sweating tending to reduce its efficiency.

It is a further object of the invention to 20 provide a device which will be automatically drained when put into service, as at the beginning of a day, and will not drip thereafter whereby continuous connection to a drain is unnecessary.

Further objects of the invention will appear from the following description when 25 read in connection with the accompanying drawings showing an illustrative embodiment of the invention and wherein:—

Fig. 1 is a perspective view;

Fig. 2 is a plan view partly broken away;

Fig. 3 is a vertical transverse section on line 3—3 of Fig. 1;

Fig. 4 is a vertical longitudinal section of 35 the upper portion only on line 4—4 of Fig. 3; and

Fig. 5 is a detail horizontal section on line 5—5 of Fig. 3.

As shown the device comprises a box 10 40 formed of porous compressed cellulosic heat insulating material, and desirably having a thickness of the walls of substantially one and five-eighths inches. The desirable thickness for the walls of the box has been determined by a large number of experiments 45 whereby it is found that a less thickness than that named is insufficient and that an increase of that thickness does not improve results in any measure comparable with the added expense.

The said box is constructed by nailing to-

gether slabs of material using rust-proof nails, screws, or the like, and the assembled box is then dipped into a water-proofing material, such as asphalt, to impregnate the surface of the insulating material and to form a 55 coating upon the surface.

The side and end surfaces of the box 10 are shown as covered with metal plates 11, which are secured to the box by being placed against the asphalt while fresh, which plates may be 60 exposed upon the outside of the device when in use and may carry advertising material.

The bottom of the box 10 is self-supporting between its edges and requires no frame 65 members therebeneath.

To hold the box 10 there are shown upper leg sections 12, 13, 14, 15, each upper leg section being supported upon a lower leg section 16, 17, 18, 19.

The connection between the leg sections 70 may take various forms but for purposes of illustration there is shown a loop 20 carried by the lower leg section and a reduced portion 21 carried by the upper leg section fitting into the angle of the lower leg section 75 and behind the loop 20.

In order to make the frame of the device such that it may be knocked down for shipment, the sections 12, 13, are permanently connected by an angle 22 and the sections 14, 80 15 by an angle 23, and the end members 24, 25 are removably connected to the sections 12, 13, and 14, 15.

The side edges of the box 10 rest upon the horizontal flanges of angles 22, 23 and the 85 end edges of the box rest upon horizontal flanges of the angles 26, 27, which are shown as formed integral with the lower portion of the end members 24, 25. To support the upper ends of the racks for containers 28 in an inclined position, one of which is shown in place in Fig. 3, the end members 24, 25 are 90 shown as connected by means of a strip 29, desirably formed as an inverted angle, the ends of which are permanently connected to the end members 24, 25 forming a unit therewith when the device is knocked down.

The lower leg sections 16, 17, and 18, 19 are respectively permanently connected by 95 means of members 30 and 31, which members 100

are formed at their upper edges with channels 32, 33 for engagement with the lower corners of racks 28 to support the same in the position shown and the sections 17, 18 5 and 16, 19 respectively are separably connected by means of bars 34, 35 respectively.

Within the box 10 there is shown a metal casing 36 which is formed fluid tight and the edges of which rise above the edges of box 10, as indicated at 37. The upper ends of leg sections 12-15 also extend above the edges of box 10 as clearly shown, and to cover the space between the upper edges of the casing 36 and the ends of legs, there is shown 15 a rectangular frame 38 having downwardly extending flanges to overlap the edges of the casing 36, the space 39 thus provided above the edges of the box 10 serving to prevent sweating or the condensation of moisture 20 upon the upper edges of the box 10, the presence of which moisture would interfere with the efficiency of the heat insulation. The flanges of frame 38 are shown as secured to the leg sections 12-15 inclusive by means of 25 cap screws 40.

The advertising matter upon the plates 11 is liable to become rapidly defaced and for the purpose of ready renewal thereof, there are shown plates 41 which may be slipped 30 between the plates 11 and the angles of the leg sections 12-15 inclusive, which plates 41 may be easily removed by removal of the frame 38.

To provide ready access to the contents of 35 the refrigerator, there is shown a cover formed in two sections 42, 43 hinged together as at 44, one section carrying a flange 45 overlying the joint to seal the same and the cover sections 42, 43 are shown as filled with heat 40 insulating material 46, handles 47, 48 being provided for convenience in opening the covers, either of which may be opened, utilizing the other thereof as a support.

To drain water from the container which 45 results from the melting of ice therein, there is shown a siphon comprising a lower portion 49 and an upper curved section 50, each screwed into an interiorly threaded collar 51 secured about an opening in the bottom of the 50 casing 36, the portion 49 passing through an opening 52 in the angle 29.

The internal diameter of the curved portion 55 of the siphon is made of such a dimension that when liquid rises to the level of the lower 55 surface of its bore at the highest point of the curve, the surface tension within the bore will start the siphon into action thereby causing the liquid in the casing to be exhausted down to the level of the end 43 of the siphon. 60 Such internal diameter is found to be substantially one-eighth of an inch. If the siphon were larger than this size there would merely take place a steady drainage when the liquid arrived at the level referred to 65 without the emptying action desired.

In the operation of the device the ice left in the device at the end of the day, or other period of use, will have melted during the night, thus providing a body of water in the casing. When the device is to be placed into operation it is filled with the containers, as bottles, and the dimensions of the casing are desirably such that the bottles may stand upright therein with their caps exposed in the manner provided by the sanitary laws of many States. When the device has been filled with bottles, cracked ice is placed about the upper portions of the bottles and between them and the ice so placed will raise the level of the water in the casing thus setting the siphon into action to draw the water down to the level of the end 53 of the siphon, a receptacle being placed under the portion 49 of the siphon to catch the water. When the siphon has ceased flowing the device may be wheeled to any portion of the sales room since the ice that will melt thereafter will not be sufficient to again cause the device to drain for a considerable period of time, usually 80 throughout the day.

As bottles are removed the ice will float in the water caused by its melting and as the ice melts the level of the water will not be raised, thereby resulting in the action above described.

The presence of a considerable volume of water in the casing is desirable as the water so present has the temperature of the ice floating therein and thus cools the bottles immersed therein.

The device may be used as a serve-yourself dispenser, the customer removing a bottle from the dispenser and paying the cashier. For the convenience of the customer a cap remover 54 is shown secured to the outside 105 of the dispenser and a receptacle 55 is shown to catch the caps as they are removed from the bottles.

Minor changes may be made in the physical embodiment of the invention without departing from the spirit of the invention, 110 within the scope of the appended claims.

I claim:

1. A refrigerator comprising, in combination, an insulating container, angle iron legs 115 each embracing a corner of said container and spaced outwardly therefrom, angle frame members each having a flange underlying a corner of said container and a vertical flange spaced from the lower edge of a side thereof, removable plates inserted in the spaces between said legs and vertical flanges and the sides of said container, an open frame supported by the upper ends of said legs and having outer flanges overlapping said removable plates and a heat insulating cover resting upon said frame serving as a closure for said container.

2. A refrigerator comprising, in combination, a frame comprising angle iron legs, 130

each leg comprising upper and lower separable sections, telescoping connections carried by the meeting ends of said sections, upper and lower horizontal members connecting
5 adjacent legs, said upper members formed with inwardly facing angles comprising vertical and horizontal flanges, a heat insulating box resting on said horizontal flanges and its corners embraced by said vertical flanges and
10 by the angles of said upper leg sections, a rectangular frame of downwardly open channel material covering the upper edges of said box, and a cover supported by said frame.

15

JOHN C. STATON.
